Technical cross-sectional diagram of a composite structure A. The diagram shows a layered construction with the following layers from top to bottom:

- Layer 22: A top layer with a hatched pattern.
- Layer 20: A layer with a grid of rectangular holes.
- Layer 30: A layer with a grid of small rectangular features.
- Layer 23: A layer with a hatched pattern.
- Layer 38: A layer with a grid of small rectangular features.
- Layer 54: A layer with a grid of small rectangular features.
- Layer 60: A layer with a hatched pattern.
- Layer 56: A bottom layer with a hatched pattern.

Arrows labeled 11 and 12 indicate the direction of material flow or pressure across the structure. The structure is labeled A at the top left and H at the bottom right.

FORREST WILLIAM MANKER, OF JACKSON HEIGHTS, NEW YORK, ASSIGNOR TO THE SURFACE COMBUSTION COMPANY, INC., OF TOLEDO, OHIO, A CORPORATION OF NEW YORK.

SHEET AND PAIR HEATING FURNACE.

Application filed September 12, 1925. Serial No 55,931.

This invention relates to improvements in furnaces and more particularly to a combined sheet and pair furnace.

It is an object of the invention to provide a combined sheet and pair furnace wherein the sheet and pair heating chambers may be efficiently heated by gas generated in coal-fired producers forming part of the furnace construction.

10 Another object is to provide a sheet and pair furnace so constructed that preheated air may be utilized to support secondary combustion of the gases entering the respective heating chambers from the producers.

15 A further object is to provide means in connection with the recuperators associated with the sheet and pair heating chambers which will permit air heated by one of the recuperators to be diverted into the channel 20 through which the air heated by one of the recuperators normally flows on its way to be mixed with the gas produced by one of the producers.

An additional object is so to construct the 25 furnace that the products of combustion leaving the sheet heating chamber may pass beneath the chamber floor and thus be caused to give up some of its heat to the floor in passing thereunder.

30 A still further object is to provide means whereby the gases generated by one of the producers may be diverted into the channel through which the gases generated in one producer normally flow on their way to the 35 heating chamber with which said producer is primarily associated.

The above and other objects of the invention will appear from the detailed description taken in connection with the accompanying 40 drawings forming part of the specification.

Referring to the drawings:

Fig. 1 is a horizontal section taken through the improved sheet and pair furnace embodying the preferred form of the invention, the view being taken substantially on line 1—1 on Fig. 4 and showing the arrangement of the gas producers with respect to the pair and sheet heating chambers and to each other.

50 Fig. 2 is a longitudinally vertical section through the sheet heating furnace and showing the arrangement existing between the gas producer, the heating chamber and the re-

cuperator, together with the various parts and 55 passageways associated therewith.

Fig. 3 is a longitudinally vertical section through the pair heating furnace and showing the preferred arrangement existing between the heating chamber, the recuperator and the gas producer, the point of entry of the 60 gases from the latter being the only part of the producer which is clearly shown in this view.

Fig. 4 is a transverse vertical section 65 through the pair and sheet heating furnace showing the relative arrangement of the heating chambers with respect to each other and with respect to their recuperators.

In the drawings, the sheet heating chamber is indicated at A, the gas producer for the 70 same at B and the recuperator forming part of the furnace construction at C. The pair or slab heating chamber is indicated at D, the gas producer for the same at E and the recuperator forming part of the furnace construction at F.

The two producers are arranged at one end of the sheet heating chamber, one of the producers opening directly into the heating chamber through the adjacent end wall and the other producer opening directly into the pair heating chamber through the adjacent side wall. The pair heating chamber is of less width than the sheet heating chamber but is longer than the latter and extends beyond 85 the end wall against which the producers abut.

The two producers have a wall 6 between them and are preferably connected by a passage 7 extending through the wall whereby 90 gases generated in one of the producers may flow into the other. This passage will normally be kept closed in any suitable manner as, for example, by a sliding door 8 of suitable refractory material, the door being operable from without the furnace in any suitable manner as by means of a rod 9 leading from the door or closure through the furnace wall.

The end wall of the sheet heating chamber against which the producers are disposed is 100 indicated at 10 and forms a dividing wall between said chamber and the two producers. That portion of the wall fronting the producer B is cut away to form a passage through which the gases from the producer B may 105 pass into the heating chamber, the producer

B being so disposed with respect to the wall that a passage 12 is formed between said wall and the top of the producer, said passage leading into a passage formed in the wall. The 5 space between the roof and the heating chamber and the top of the wall 10 forms in effect a combustion chamber 14.

Air for supporting secondary combustion of the producer gases is supplied through 10 ports 16 (Fig. 2) which lead downwardly from the top of the dividing wall 10 to a transversely extending passage 18 within the wall. Passage 18 is in communication with a hot air collecting chamber 20 by means 15 of suitable passages 22, the air collecting chamber being formed above the recuperator C. The fresh air heated by the recuperator is supplied therebeneath by way of suitable passages 23 (Figs. 2 and 4).

20 The recuperator C is heated by the products of combustion flowing from the sheet heating chamber. The burned gases after reaching the far end of the chamber opposite the producer, which is the end through 25 which the work is removed from and entered into the chamber, passes through corner ports 24 in the chamber floor at either side of the work door 26 of the chamber into a transversely extending passage or conduit 28 (Fig. 30 2) from which run longitudinally extending passages 30 which in turn open on a downwardly extending passage 32. The recuperator C fronts on this passage 32 and consequently the products of combustion will flow 35 through the recuperator the latter being of hollow tile construction, as clearly indicated in Fig. 4. The air to be heated circulates between the tiles in grooves or channels surrounding the tiles.

40 It is preferred that the products of combustion shall pass through the upper portion of the recuperator and to return through the lower portion thereof. To this end a passage 32 terminates approximately mid-way 45 the top and bottom of the recuperator, the baffle plate 33 forming the bottom of the passage. The products of combustion after passing through the upper portion of the recuperator enter a passage 34 on which the other end 50 of the recuperator fronts and then pass through the lower portion of the recuperator and into the passage 35 below the baffle 33 this passage 35 leading to the stack G by way of a suitable passage 36 (Fig. 1) at one 55 side of the furnace.

Access may be had to the conduits 28 and 30 for the purpose of cleaning the same through clean-out ports 29 extending through the furnace wall, these clean-out ports being 60 normally kept closed by suitable plugs.

Coming now to a description of the pair or bar furnace, it will be noted that the gas generated in the producer E enters the pair heating chamber D through a transversely 65 extending opening 50 (Fig. 3) formed in the

side wall 51 opposite the producer. Air for supporting secondary combustion of the producer gases is supplied through ports 52 which lead downwardly in the side wall where it fronts the recuperator, these ports 70 52 communicating with a transversely extending passage 53 in the wall, said passage 53 communicating with an air collecting chamber 54 (Figs. 3 and 4) formed above the recuperator F, communication being had by 75 suitable passage 55, it being understood that the recuperator is heated by the products of combustion flowing from the chamber D as will presently be explained. Air is admitted to the recuperator at the bottom 80 thereof through suitable passages 56 and circulates around the tiles of which the recuperator is formed in a manner already explained in connection with the sheet heating furnace.

85 Extending longitudinally with the chamber D are two parallel tracks or piers 58 on which pairs or slabs X are supported as they are moved through the chamber. These tracks or piers are arranged in spaced relation 90 to the sides of the chamber and with respect to each other whereby side and central channels are formed. The burning gases in circulating in the chamber will pass around the slabs and between the same and some of the 95 hot gases will find their way into the said channels. In order to permit free circulation of the hot gases from one channel to another the piers are pierced by ports or 100 passages 60. The floor of the chamber at the far end of the same is pierced by ports 62 through which the products of combustion flow into a downwardly extending passage 64 which fronts on the upper portion of the recuperator, the bottom of the passage 64 being indicated at 66. The products of combustion upon entering the passage 64 pass 105 through the upper portion of the recuperator into a passage 67 on which the other end of the recuperator fronts. Upon reaching 110 this passage 67, the gases pass through the lower portion of the recuperator and enter a passage 68 which leads to a side passage 69 (Fig. 1) which in turn communicates with the stack G.

115 The work door of the chamber D is indicated at 70 and is on a level with the tracks or piers 58. In order to permit the channels to be cleaned out, clean-out ports 71 are provided in the furnace wall below the door 70.

120 It will be noted that the tracks or piers 58 on which the slabs or pairs X are supported are shown as arranged on an incline, the gradient running upwardly from the point of entry of the slabs into the chamber 125 toward the door 70 through which they are removed. By providing the piers or tracks with a gradient of the character specified, the slabs X may be more readily held in a sloping position to prevent them from fall- 130

ing forwardly toward the door 70 as they are moved through the chamber. After the slabs or pairs have been entered into the chamber they are prevented from falling on 5 their sides toward the point of entry by any suitable means such as dogs 72 mounted on the furnace wall.

No claims are made to the inclined tracks in this application inasmuch as claims covering 10 that feature are made in a pending application.

The air chambers 20 and 50 above the recuperator C and F are normally independent of each other. However, it is preferred to 15 provide a conduit or passage 73 between them so that if found desirable hot air from one chamber may flow into the other, it being understood that any suitable closure means generally indicated at 74 will normally keep 20 the passage closed.

The preferred arrangement by which the gas producers are connected together and the recuperators are connected together gives a very flexible means of operating the furnace. 25 This construction does not necessitate the careful watching of each producer to see that it produces only such amount of gas as each separate furnace requires but the producers may be operated at any desired rates and one 30 may be used to supplement the other in taking care of the necessary heat requirements. Furthermore, if the heat requirements fall it is possible to operate one producer to provide for heating both furnaces. The arrangement by which preheated air may be transferred 35 from one recuperator to another allows for the efficient heating of the air which is used in combustion and if one recuperator does not supply the suitable amount of air 40 for burning the combustion gases of a producer furnace, this recuperator may be supplemented by the other recuperator.

What is claimed is:

1. In a sheet and pair furnace, the combination of two heating chambers arranged 45 side by side with a dividing wall between them, a recuperator below each chamber, a gas producer at one end of one of said chambers, there being an opening in said dividing 50 wall through which the gases generated in the producer are entered into the adjacent chamber, a second producer arranged alongside the first, there being an opening in the end wall of the other chamber through which

gases generated in the second producer are 55 entered, means for leading the products of combustion of the respective chambers to and through the respective recuperators whereby the latter may be heated, means for supplying 60 fresh air to the recuperators for heating, 65 means for conducting the heated air to the respective points of entry of the producer gases into the chambers, and means between the two producers permitting gases generated in the one to mingle with the outflowing gases 70 in the other.

2. In a furnace, the combination of a heating chamber having an opening in one end wall over which combustible gases may be entered into the chamber and having a work- 75 door in the other end wall, means for conducting the products of combustion from the chamber and beneath the floor thereof comprising a conduit extending transversely beneath the floor and opening into the chamber 80 at the corners on either side of the work-door, branch conduits leading from said conduit toward the opposite end of the chamber, a recuperator through which the products of combustion flow before passing to the stack, 85 and conduits leading from the recuperator to and through the end wall over which the combustible gases pass whereby air pre-heated by the recuperator may mingle with said gases to support secondary combustion 90 thereof.

3. In combination, a pair of independent heating chambers, a plurality of gas producers for supplying gas to said chambers, a recuperator for each heating chamber, and 95 means permitting the air heated by one recuperator to be diverted into the flow channel for the air heated by the other recuperator.

4. In combination, a pair of independent 95 heating chambers, a plurality of gas producers for supplying gas to said chambers, a recuperator for each heating chamber, means permitting the air heated by one recuperator to be diverted into the flow channel 100 for the air heated by the other recuperator, and means permitting gas generated by one producer to be diverted into the channel through which the gas from the other producer normally flows. 105

In testimony whereof I affix my signature.

FORREST WILLIAM MANKER.
